DESIGN FOR A CHARM OR SIMILAR ARTICLE

Tracy L. Carpenter, Lindenhurst, N. Y.

Application May 9, 1944, Serial No. 113,526

Term of patent 7 years

(Cl. D45—15)

To all whom it may concern:

Be it known that Tracy L. Carpenter, a citizen of United States and resident of Lindenhurst, in the county of Suffolk and State of New York, has invented a new, original, and ornamental Design for a Charm or Similar Article, of which the following is a specification, reference being had to the accompanying drawing, forming part thereof, and in which,

Fig. 1 is a front elevational view of the charm or similar article, embodying my new design;

Fig. 2 is a side view thereof; and
Fig. 3 is a top view.

The instant design is characterized by the specific configuration of the charm, said charm having transparent and opaque areas, all as shown.

I claim:

The ornamental design for a charm or similar article, substantially as shown and described.

TRACY L. CARPENTER.
